DIVING WATER GLIDER

George Loeffler, 45 Crabapple Drive,
Barrington Hills, Ill.

Filed Jan. 25, 1967, Ser. No. 5,568

Term of patent 14 years

(Cl. D71—1)

FIG. 1

FIG. 2

FIG. 3

FIG. 4

FIG. 5

FIG. 6

FIG. 1 is a perspective view of a diving water glider showing my new design in full lines;

FIG. 2 is a side elevational view, the opposite side being substantially a mirror image thereof;

FIG. 3 is a top plan view thereof;

FIG. 4 is a bottom plan thereof;

FIG. 5 is a front elevational view thereof; and

FIG. 6 is a rear elevational view thereof.

The broken line showings of a human being and a tow cable in FIG. 1 are for illustrative purposes only.

I claim:

The ornamental design for a diving water glider, as shown and described.
